Patented July 27, 1915.

UNITED STATES PATENT OFFICE.

JOSEPH L. DYSON, OF LOYALTON, CALIFORNIA.

WELL-DRILLING APPARATUS.

1,148,366.

Specification of Letters Patent. Patented July 27, 1915.

Application filed November 13, 1913. Serial No. 800,766.

To all whom it may concern:

Be it known that I, JOSEPH L. DYSON, a citizen of the United States, and a resident of Loyalton, in the county of Sierra and State of California, have invented an Improvement in Well-Drilling Apparatus, of which the following is a specification.

My present invention relates to drill turners and more particularly to that class of automatic arrangements for this purpose utilized in connection with well drilling operations, and my object is to provide a simple and inexpensive attachment whereby the desired result may be accomplished in a novel and effective manner and through the action of the trip rod and the impact of the drill upon each stroke thereof.

In the accompanying drawing which illustrates my invention, Figure 1 is a side elevation illustrating my invention. Fig. 2 is a detail horizontal section taken substantially on the line 2-2 of Fig. 1.

Referring now to these figures, A indicates upright surface guides upon which are slidably disposed the vertical tubular ends b of a cross head B, acting as a guide for the movement of the drill C, the rod of the latter of which is connected to the lower end of a water swivel D, to the upper end of which water swivel is connected the lower end of a swivel rod E. As seen in Fig. 1, the central portion of the cross head guide B is depressed in substantially U-shaped form and through the base b' of which depression is loosely extended the upper extremities of the swivel rod E, having a nut or head e above the base b' of the depression and being provided with a spring e' coiled thereabout and compressed between the lower surface of the base b' of the depression and a collar e² secured thereon, it being thus apparent that upon impact of the drill within the base of the opening being drilled, relative movement of the drill including the swivel rod E, will take place with respect to the cross head guide B, under tension and control of the spring e'.

To the angular sides b² of the central depression of the cross head guide B are pivotally connected the upper inner ends of curved levers F and F', the upper inner portions of which, adjacent their pivots, extend along side one another within the central depression of the cross head guide and are engaged by a yoke or clevis g to which the trip rope G is connected.

The lower outer ends of the levers F and F' are laterally off-set so that they depend upon relatively opposite sides, and adjacent relatively opposite ends, of a frame H centrally journaled upon the swivel rod E below its collar e². This frame H consists of upper and lower plates, the intermediate portions of which are spaced apart and the ends of which are bent angularly together and rigidly connected, and extend respectively above and below a ratchet wheel I mounted therebetween and secured upon the swivel rod E, the frame carrying a pair of spring controlled pivoted pawls h, in engagement with the teeth of the ratchet wheel I upon relatively opposite sides thereof.

The lower outer ends of the levers F or F' before mentioned are provided with pivoted links f and f', projecting toward relatively opposite ends of the frame H and connected to the respectively adjacent sides thereof by means of lugs h' projecting from the frame. It will thus be seen that the vertical movement of the trip rope G which is usually operated from a derrick will, through the loose connection of the lower end of this rope to points intermediate the ends of levers F and F' curved as described, tend to cause outward movement of the lower ends of these levers in relatively opposite directions and this movement, through the links f and f', will be communicated to the frame H so as to swing the latter horizontally upon the swivel shaft E in the direction of the arrow shown in Fig. 2. In this movement it will be noted that the pawls h will be in positive engagement with the teeth of the ratchet wheel I and will consequently cause slight rotative movement of the ratchet wheel and the swivel rod E to which the ratchet wheel is connected, effecting similar rotative movement of the drill C through the water swivel D. Thus it will be seen that upon each upward movement of the drill C, a slight rotative movement will be imparted thereto and it will be further seen that upon each descending stroke of the drill, the frame H will be given a slight rotative movement in the reverse direction to enable its pawls h to seek a new hold upon the ratchet wheel I. This latter movement is accomplished by virtue of the relative movement of the swivel rod E with respect to the cross guide B, such movement of the swivel rod causing similar vertical movement of the frame H, at the same time drawing the lower ends of the levers F and

F' inwardly and swinging the frame H back to its original position. In this manner oscillatory movement is communicated to the frame H during each complete stroke of the 5 drill C and this oscillatory movement is transmitted to the drill rod in such a manner as to effect a step by step rotation of the latter.

I claim:—

- 10 1. The combination of a cross head having guided movement and provided with a centrally depressed portion having angular sides, a swivel rod the upper end of which is loosely extended through the base of the 15 depressed portion of the cross head whereby to permit of limited relative movement therebetween, a spring carried by the swivel rod whereby to cushion the relative movement, a horizontal frame centrally journaled 20 on the swivel rod and provided with a pair of spring controlled pawls, a ratchet wheel secured upon the swivel rod within the frame and with which the pawls are engaged, a pair of curved levers having their 25 upper inner ends lapped within the depending portion of the cross head and pivotally connected at their extremities to relatively opposite sides of said depending portion, the lower outer ends of said levers extending 30 upon relatively opposite sides, and adjacent relatively opposite ends, of the frame, links pivotally connected to the lower portions of the levers, said links extending in relatively opposite directions and also pivotally connected to portions of the frame, a 35 yoke or clevis loosely engaging the upper lapped portions of the levers, a trip rope connected to the yoke or clevis, and a drill rod connected to the lower end of the swivel 40 rod, all for the purpose described.
2. The combination of a swivel rod to the lower end of which the drill is connected, a cross head having a vertical guided movement and with which the upper end of the 45 swivel rod is vertically movably connected, a frame mounted to oscillate on the swivel

rod, a pawl and ratchet connection between the frame and swivel rod, levers pivotally connected at their upper ends to the cross head and having linked connections at their 50 lower ends with relatively opposite sides, and adjacent relatively opposite ends, of the oscillatory frame, and a trip rope having connection with the said levers intermediate their ends.

55

3. The combination of a swivel rod to the lower end of which the drill rod is connected, a horizontal frame mounted to oscillate on the swivel rod and having a pawl and ratchet connection with the said swivel rod, 60 a pair of levers having oppositely extending links at their lower ends connected to relatively opposite sides of the frame and having inwardly curved and lapping upper ends, a vertically movable guide member 65 with which the said upper ends of the levers are pivotally connected at their extremities, a yoke or clevis embracing the lapped upper portions of the levers, a trip rope connected to the yoke or clevis, and a movable connection between the support and the upper 70 end of the swivel rod, all for the purpose described.

70

4. The combination of a vertically movable cross head, a swivel rod having a vertically movable connection with the cross head, an oscillatory frame mounted on, and having a pawl and ratchet connection with, the said swivel rod, levers pivoted at their upper ends to the cross head and having 75 linked connections at their lower ends with relatively opposite sides of the frame and adjacent relatively opposite ends thereof, a drill rod connected to the lower end of the swivel rod, and a trip rope for lifting the 80 cross head and drill rod, having connection with the said levers intermediate the ends of the latter, all for the purpose described.

JOSEPH L. DYSON.
